CLAIM

The ornamental design for a stationary photo booth, as shown and described.

DESCRIPTION

FIG. 1 is a front perspective view of a stationary photo booth, showing our new design;

FIG. 2 is a rear perspective view thereof;

FIG. 3 is a bottom perspective view thereof;

FIG. 4 is a front view thereof;

FIG. 5 is a right side view thereof;

FIG. 6 is a rear view thereof;

FIG. 7 is a left side view thereof;

FIG. 8 is a top view thereof; and,

FIG. 9 is a bottom view thereof.

The broken lines depict features of a stationary photo booth that form no part of the claimed design.

1 Claim, 9 Drawing Sheets
